The Babcock & Wilcox Company, Bayonne,
N. J., a corporation of New Jersey

Application April 27, 1931, Serial No. 533,067

3 Claims. (Cl. 122—302)

This invention relates to boilers associated with a furnace and more particularly to boilers wherein material containing a high content of non-combustible matter is utilized as a fuel.

5 In many industrial processes combustible materials are produced that are burned to produce some desirable by-product, and this invention contemplates a boiler associated with a furnace especially designed to utilize the heat of combustion of a product such as the black liquor which comes from digesting vats of a wood pulp fibre plant, and is processed by burning.

10 The boiler and furnace contemplated in this invention are also useful in burning other fuels, and an effective furnace temperature control is provided as a part of this invention, to aid in the successful combustion of fuels that are difficult to burn. For example, when fuel which has a high aqueous content is used it must be dried before effective combustion takes place, hence, when such fuel is to be burned the furnace walls and roof should be cooled to a lesser degree than when a dry fuel, such as pulverized coal, is used.

15 In connection with the use of wet fuel, it is extremely desirable to locate the fuel inlet at the top of the furnace setting, so that the fuel may be projected through combustion gases at high temperatures and hence more quickly dried.

20 An object of the invention is to provide a boiler associated with a furnace, wherein a fuel is used that has a high content of non-combustible material.

25 A specific object of the invention is to provide a boiler associated with a furnace wherein the black liquor from digesting vats in wood pulp plants is utilized as a fuel to be burned in the furnace, and especially contemplates a boiler structure suitable for this purpose.

30 Further objects will be apparent to those skilled in this particular art from the claims and the description in the specification in connection with the drawings, in which—

35 Fig. 1 is a sectional side view of a boiler and a furnace forming an illustrative embodiment of the invention, and

40 Fig. 2 is a sectional plan view taken along the line 2—2 of Fig. 1.

45 In the embodiment of the invention which has been chosen for purposes of illustration, a combustion chamber 1 is provided that is especially adapted to burn a fuel which has a high content of non-combustible material. In the lower part of the combustion chamber is provided a tap 2 for the removal of the unburned portion of the fuel, which, when the fuel is black liquor from a wood pulp fibre process, is termed smelt, and is removed for further treatment for obtaining valuable by-products therefrom.

50 Above the tap 2 are inlets 3 which may be arranged in rows, through which a processing ma-

5 terial may be admitted to mix with the liquor to be burned for the purpose of promoting desirable chemical reactions and through which air may be directed against the material to promote combustion. Another inlet 4 is provided in the upper portion of the furnace to admit the liquor which is to be processed and burned.

10 At the top of the combustion chamber is a row of roof tubes 5 connected at one end to and supported by a steam and water drum 6 and at its other end to a header 7. The ends of the tubes adjacent the header 7 rest upon a portion of the furnace setting and are supported thereby free to expand. This row of tubes 5, in addition to forming a part of the steam generating system, 15 acts to shield the furnace roof from the shock of direct heat from the burning fuel, and by virtue of the heat absorbing medium which is circulated through them keeps the roof cool, and at the same time acts as a partial support for the 20 roof, hence providing a simple and cheap roof construction. In addition, they serve to aid in the control of the furnace temperature.

25 As best shown in Fig. 2, header 7 is supplied with water from a drum 6 by feed pipes 23 which are connected to the header 7 at each end thereof. Water from the drum flows through the downcomers 25 to the headers 24, and then through pipes 23 to the header 7. The water and any steam that is generated then flows up the 30 tubes to the drum 6 to complete a steam and water circulatory system.

35 Disposed beyond a refractory structure 8, which forms a partition that partially separates the combustion chamber from the boiler gas pass, 35 is a boiler of the Stirling type, which, in this instance comprises a pair of upper drums 6 and 9 connected together by steam circulators 10 and water circulators 11, and which are further connected together by banks of tubes 12 and 13, 40 through a lower drum 14.

45 The partition 8 shields the lower portion of the furnace from the cooling effect of the steam generating tubes, and thus aids in the combustion of the liquid fuel. At the same time the partition 8 concentrates the direct heat of combustion from the burning fuel against the roof and so necessitates the provision of a protective device such as the roof tubes previously described, to prevent destruction of the roof structure. This 50 is especially true when black liquor is burned, for hot combustion gases from such a fuel have a destructive effect on furnace brick work. The partition 8 is also hollow, so that air may be circulated through it to aid in the control of the 55 furnace temperature.

55 The front row of tubes 15 of the bank 12 is more widely spaced than the other tubes of the bank as best shown in Fig. 2, and acts as a slag screen for the rest of the tubes; and disposed be- 60

low these tubes is a pit 16 especially adapted to receive slag and ash checked by the tubes 15. An opening 17 is provided in the pit to readily provide for the removal of this slag and ash. The 5 tubes 15 are vertically inclined so that the molten solids checked thereby drop into the hopper 16 and radiate back heat.

A row of tubes making up a superheater 20 is connected at one end directly to the steam space 10 of the drum 9, and is curved to extend downward parallel to the tubes of the bank 13 for the greater portion of its length in a hairpin bend.

The other end of the row of tubes of this superheater is secured to an outlet header 21 disposed 15 between the drums 6 and 9. The header 21 is shielded from contact with combustion gases by a roof baffle member 22.

The superheater as just described is especially desirable in a boiler-furnace organization such 20 as the one herein described, for in addition to the elimination of an inlet header the tubes are so disposed with respect to the flow of combustion gases during the operation of the device that while presenting an adequate superheating heat 25 transfer surface to the sweep of gases, they present a minimum surface upon which soot, ash, and slag will be deposited.

In the operation of the device when black 30 liquor is used as a fuel, in starting, a fire is built in the lower portion of the furnace 1 to heat the floor and side walls. When this heating has been accomplished normal operation is ready to be started. The black liquor is admitted to the combustion chamber by means of the inlet 4 and 35 is ignited by the fire. From this time on combustion continues as long as black liquor is supplied. While this combustion is taking place an additional chemical reaction is transpiring in the unburned molten mass at the bottom of combustion 40 chamber 1 due to the influx of processing material and air through the inlet 3.

A portion of the downwardly projected fuel 45 from the inlet 4 is ignited by the heat in the combustion chamber. The flames and combustion gases that result from this ignition, by virtue of the location of the inlet, initially are projected and travel downwardly, so that when their direction of travel is reversed and the gases of combustion are reflected upwardly by the 50 molten mass in the bottom of the furnace, a large portion of the unburned fuel and molten non-combustible material is separated from the combustion gases and is projected to the bottom of the combustion chamber. The unburned 55 combustible matter so projected joins the molten mass of material being processed and is burned.

Combustion gases from this operation strike the cool roof tubes and are deflected through the several gas passes as indicated by arrows. The 60 first gas pass is downward to augment the removal of solids. The hopper 16 is also a reversing chamber, so that a portion of the solids that might ordinarily not be removed from the furnace gases by the slag screen tubes 15, are removed by the reversing action of the gases. The 65 freezing solids are allowed to accumulate in the hopper and they radiate heat to the steam generating tubes as they cool, so that part of the heat which generates steam is salvaged from 70 cooling solids.

When the gases strike the row of tubes 15, which as aforesaid act as a slag screen for the

other tubes, much of the remaining ash and other non-combustible material that is swept along by the combustion gases cool and drop to the bottom of the pit 16 so that the gases of combustion that sweep successively along the tubes of the banks 5 12 and 13 and across the tubes of the superheater 20 in gas passes defined by the baffles 30, are comparatively free from solid non-combustible material. After sweeping along the tubes in the rear of bank 13 the combustion gases flow 10 through a suitable gas outlet 31.

A boiler associated with a furnace has been described in some detail as utilizing the black liquor from digesting vats of a wood pulp fibre plant as a fuel, but obviously the device shown 15 and described is especially adapted for use with any fuel which has a high content of non-combustible material, and although a specific structure has been described in some detail, it is to be understood that changes, additions, substitutions and omissions may be made therein within the spirit of the invention as defined by the appended claims.

I claim:

1. In a steam boiler associated with a furnace 25 having an inclined roof, an upper drum, a lower drum connected thereto by steam generating tubes arranged to form a primary steam and water circulatory system, a row of radiantly heated riser tubes disposed along the furnace roof and connected at one end to said upper drum and at the other end to a header, and conduit members independent of said steam generating tubes joining said header with said upper drum to form a secondary steam and water circulatory system, said 30 conduit members being connected to said upper drum mainly below the level of the connections of said roof tubes to said drum.

2. In a steam boiler associated with a furnace having an inclined roof, an upper drum, a lower 40 drum connected thereto by steam generating tubes arranged to form a primary steam and water circulatory system, a row of radiantly heated riser tubes disposed along the furnace roof and connected at one end to said upper drum and at the other end to a header, and conduit members independent of said steam generating tubes joining said header with said upper drum to form a secondary steam and water circulatory system, said 45 conduit members including a group of downcomer tubes connected to said upper drum in a circumferential row mainly below the level of the connections of said roof tubes to said drum.

3. In a steam boiler associated with a furnace having an inclined roof, an upper drum, a lower drum connected thereto by steam generating tubes arranged to form a primary steam and water circulatory system, a row of radiantly heated riser tubes disposed along the furnace roof and connected at one end to said upper drum and at the other end to a header, and external conduit members independent of said steam generating tubes joining the opposite ends of said header with the corresponding ends of said upper drum to form a secondary steam and water circulatory system, said conduit members including a group of downcomer tubes connected to said upper drum in a circumferential row mainly below the level of the connections of said roof tubes to said drum.

HERMAN B. SMITH.
